UNITED STATES PATENT OFFICE

GERALD J. HENRY, OF BOSTON, MASSACHUSETTS, ASSIGNOR TO PASS & SEYMOUR,
INC., OF SCLVAY, NEW YORK, A CORPORATION OF NEW YORK

LOCKING SOCKET

Application filed August 20, 1928. Serial No. 300,777.

This invention relates to lamp receptacles or sockets, and more particularly to lamp sockets provided with means for locking lamps therein.

It is a general object of the present invention to provide a novel and improved form of lamp socket with locking device.

More particularly, it is an object of the invention to provide, in a socket equipped with a lamp locking device, a guide means or track for the key adapted to engage the locking device in order that it may more readily be guided to the locking device, particularly where the socket is in a deep reflector and there is but little space between the lamp and the reflector.

Other and further features and objects of the invention will be more apparent to those skilled in the art upon consideration of the accompanying drawings and following specification, wherein is disclosed a single exemplary embodiment of the invention with the understanding, however, that such changes may be made therein as fall within the scope 25 of the appended claims without departing from the spirit of the invention.

In said drawings:

Fig. 1 is a side elevation of a lamp socket equipped with the present invention, a portion thereof being broken away to show the locking mechanism; and

Fig. 2 is a front elevation thereof.

It has heretofore been customary to equip certain lamp receptacles or sockets with some form of locking means to prevent the unauthorized removal of lamps from the sockets. Such locking means are often operated by the actuation or manipulation of a spindle or similar device by means of a suitable key or wrench. Often such a key or wrench must be of considerable length to reach between a lamp and a deep reflector which may be supported from the same socket. Often-times, as shown in Fig. 1, there is but little space between the lamp and the reflector, and it is difficult to locate the position of the locking means around the periphery of the socket and to engage the key with the locking means. The present invention contemplates, therefore, the provision of a convenient guide

means into which the end of the key may be placed without difficulty so that the key may be followed along the guide until it engages the locking means.

In the drawings, 10 is the main shell or outer casing of a lamp receptacle, commonly known as the reflector type, having the removable base 11 between which and the main shell the flange 13 of a reflector 14 may be engaged. In the present instance, the socket is provided in the central recess with a conventional screw shell 15 adapted to engage the threaded portion on the base of a lamp 16 in the usual manner. A locking mechanism 18 is adapted to project a suitable locking member 19 through an opening 20 in the screw shell to engage the base of the lamp and prevent the same from being rotated. Any suitable form of locking mechanism may be employed, but it is preferred to use one of the types disclosed in the applications of Daniel M. LeFever, Serial No. 196,060, filed June 2, 1927, and Mark N. Russell, Serial No. 274,919, filed May 3, 1928. These locking mechanisms and others operate by the rotation of a suitable shaft or spindle 21 which usually has an irregular shaped head 22 engageable by a socket of complementary shape on the head 23 of a long handled wrench or key 24. The handle of the key is of sufficient length so that it is convenient to reach in between the lamp 16 and the reflector 14 which may be quite close to the lamp as shown. Here the reflector is deep, and in a dark position it is sometimes difficult to locate the locking mechanism.

To obviate this difficulty, the surface of the outer shell of the socket through which the key is adapted to project to engage the locking mechanism is provided with a track or guide means to lead the key to the locking means. In the present instance the locking mechanism is largely received in a recess 25 which opens into the front face 26 of the shell member 10. A suitable guide means such as the shallow groove 27 is arranged around this face, as best shown in Fig. 2 and the opposite ends of the groove enter the recess 25. Preferably the end 22 of the locking spindle is below the bottom of this groove

so that the key will drop on the same without any difficulty when it moves from the groove into the recess.

It has been found in actual practice that a considerable saving in time is effected where the present invention is used in sockets of the type shown, and others, where glassware and shades obstruct ready access to the locking mechanism. Not only is considerable time saved, but the possibility of breaking lamps, glassware, shades and the like is largely overcome, both when inserting new lamps and when removing old ones, both of which times require that the lamps be dark.

Having thus described the invention, what is claimed as new and desired to be secured by Letters Patent is:

1. In a lamp socket, in combination, an outer shell, a screw shell therein, a flat annular peripheral face on said outer shell adjacent the open end of said screw shell, a lamp locking mechanism for said socket having an operator engageable through an opening in said face, said face having a grooved track thereon including said opening concentric with said screw shell to guide a key to said operator.
2. The combination with a deep reflector, of a lamp socket mounted at the apex of said reflector, a screw shell in said socket, a lamp in said screw shell and having a portion in proximity to the reflector, a locking means for said lamp having an operator engageable by a key passing between the said lamp and reflector and a circumferential guide groove on said socket to lead the key directly to the operator.

In testimony whereof I hereunto affix my signature.

40. GERALD J. HENRY.
